UNITED STATES PATENT OFFICE.

EDMUND GARSIDE, OF DARLINGTON, ENGLAND, ASSIGNOR TO ENGINEERING INSTRUMENTS LIMITED, OF DARLINGTON, ENGLAND, A CORPORATION OF GREAT BRITAIN AND IRELAND.

STARTING-SWITCH FOR ELECTRIC MOTORS.

942,960.

Specification of Letters Patent. Patented Dec. 14, 1909.

Application filed September 8, 1909. Serial No. 516,680.

To all whom it may concern:

Be it known that I, EDMUND GARSIDE, a citizen of Great Britain, residing at Darlington, in the county of Durham, England, have invented new and useful Improvements 5 in Starting-Switches for Electric Motors, of which the following is a specification.

This invention relates to improvements in starting switches for electric motors of that 10 class in which a series of resistances are gradually cut out of the motor circuit under dash-pot control when the current is first switched on and in which the switch is held on by a "no volt release" arrangement.

15 The object of the invention is to construct such a device in a simple and effective manner, with little or no risk of derangement and to be operated by a simple push into the "closed" position.

20 In order that this invention may be the better understood, I will now proceed to describe the same, in relation to the accompanying drawing, reference being had to the letters marked thereon.

25 Like letters refer to like parts in the various figures.

Figure 1 is a front elevation of a switch made in accordance with my invention, the switch arm being shown in the open position. Fig. 2 is a side elevation of the same, 30 partly in section, the switch arm being shown in dotted lines in the position in which the tripping action is about to commence.

Upon a suitable base *a* I pivot a switch 35 arm *b* having contacts *c* adapted to make contact with the main terminals *d*. This switch arm is so hung upon its pivot, that when unrestrained it falls under the action of gravity into the open position. Upon the 40 base *a* is also arranged a series of resistance contacts *e* connected up in the usual way with a series of resistances inclosed within the casing *f*.

The switch arm *b* is provided with a magnetic armature *g* which co-acts with the 45 poles *h* of the electric magnet *i* rigidly mounted on the base *a*, so that the main switch is held in the closed position electromagnetically so long as the electromagnet is 50 properly energized.

Over the resistance contacts *e* the moving bridge contact *j* is adapted to slide. The 55 contact *j* is rigidly mounted on a tube *l* which at its upper end slides on, and is guided by a cylindrical stem *m* while at the

lower end the piston *n* with valve *o* is arranged, a spiral spring *p* being contained within the tube *l* so as to force the piston *n* in a downward direction while reacting against the cylindrical stem *m*, during 60 which movement the resistances are being gradually cut out of the motor circuit. The piston *n* is contained within a cylinder *q* firmly supported on the base *a* and the whole forms when filled with liquid a dash-pot of 65 ordinary construction.

To the switch arm *b* is pivoted a detent *r* having a recess *s* at its outer end adapted to engage with the roller *t*, pivotally mounted on the sliding contacts *j*, the angle contained by the detent *r* and switch arm *b* being such that when the switch arm *b* is pressed in the direction to close the main switch such movement is transmitted through the sliding carrier *j* so as to raise it into the upper position 70 on the resistance contacts *e*, until nearing the end of its stroke, the bevel edge *u* of the detent *r* comes in contact with a pin *v* mounted on the rigid bracket *w* whereby the recess *s* is withdrawn from the roller *t*, just at the 75 point of closure of the main switch. When this takes place the sliding contacts *j* are gradually forced downward slowly by the spiral spring *p* under the control of the liquid beneath the piston *n*. The main switch 80 remains in its closed position until the electromagnet *i* is short circuited or the current is cut off the main circuit from the source of supply.

It will be noted that unless the switch arm *b* is drawn back sufficiently far to properly cause the detent *r* to engage the roller *t* in order to be in a position to put the resistances 85 into the circuit, the beveled ends of the detent *r* passes to the rear side of the pin *v* 90 and prevents the main switch being closed.

The detent *r* is spring pressed by a spiral spring *x* so as to maintain it in its extended position to insure proper co-action with the 95 sliding contacts *j*.

I claim:

1. In a device of the class described, a base, a switch arm movable toward and away from the said base, and pivoted to the latter, main terminals on said base, a contact 105 on said switch arm and arranged to engage with the main terminals when the arm is moved toward the base, a series of resistance terminals on the base, a dash pot superposed on the base directly above said resistance 110

terminals, a piston working in said pot, a carriage fixed to the piston, a contact on said carriage and engageable with the resistance terminals, and means releasable to unite the carriage and the switch arm during the movement of the latter toward the base.

2. In a device of the class described, a base, main terminals mounted thereon, resistance terminals disposed on the base in substantial alinement with the main terminals, displaceable means traveling above the resistance terminals, a contact having connection with the displaceable means and engageable with the resistance terminals, and pivotal means on the base and having a contact for engagement with the main terminals upon movement in one direction of said pivotal means, and also having detachable connection with the displaceable means to effect engagement of the contact carried by the latter with the resistance terminals during said movement of the pivotal means.

3. In a device of the class described, a base, main terminals mounted thereon, resistance terminals disposed on the base in substantial alinement with the main terminals, displaceable means traveling above

the resistance terminals, a contact having connection with the displaceable means and engageable with the resistance terminals, pivotal means on the base and having a contact for engagement with the main terminals upon movement in one direction of said pivotal means, and also having detachable connection with the displaceable means to effect engagement of the contact carried by the latter with the resistance terminals during said movement of the pivotal means, a lug on the displaceable means and engageable and disengageable by said connection between the pivotal means and said displaceable means, a stop to act upon the said connection for releasing it from the lug at a predetermined point of movement of said pivotal means, and means to restore the displaceable means to its primary position when released by the said connection.

In testimony whereof I have signed my name to this specification in the presence of two subscribing witnesses.

EDMUND GARSIDE.
